SECTION INSULATOR FOR TROLLEY SYSTEMS

Lon C. Spencer, Indianapolis, Ind.

Application June 26, 1936, Serial No. 87,359

9 Claims. (Cl. 191—39)

My invention relates, generally, to overhead trolley systems, and it has reference in particular to section insulators for overhead trolley systems.

Generally, it is desirable to sectionalize the power supply for overhead trolley systems. That is, instead of having one continuous overhead trolley line with power supplied from a number of sub-stations, the trolley line is sectionalized, each section being insulated from the other and fed through a separate feeder. In this way, should a fault such as a grounded trolley wire occur in one section, the other sections will not be affected. Continuity of service is thus improved, and also a more balanced loading of sub-stations is secured, as the length of line which any one sub-station may feed is limited.

In trolley bus power systems, both the positive and negative conductor must be carried over-head as there is no ground return, the bus being insulated from the ground by rubber tires. This greatly complicates the construction of the overhead trolley at intersections, as it is necessary to provide insulating means between the conductors of opposite polarity where they intersect. This is usually accomplished through the use of section type insulators together with the necessary interlocking end fittings, and the usual metallic frogs or crossings.

As such an insulator is inserted directly into the line, it must withstand the full tension of the conductor, which may amount to from 2000 to 4500 lbs. This necessitates that the insulators not only have good dielectric qualities but also have a high tensile strength. In addition, as the insulator is directly exposed to the effects of the weather, a further requirement is that it be unaffected by moisture, heat, cold, etc.

These factors make the selection of a material for the body of a section insulator a difficult matter. Fiber, which has been used to a great extent, is a good insulator and has a high tensile strength, but in applications where continually subjected to moisture, such as in locations along the seacoast, it has shown a decided tendency to swell. In some installations the swelling has been so serious as to hinder the passage of the current collector. Further exposure to moisture has resulted in a warping and buckling of the body member, and in many cases, complete failure through softening of the fibers.

Hickory, which is one of the best insulators, is rapidly becoming scarce, and even the best hickory when impregnated is in time decidedly affected by weathering. Also, in order to secure

the necessary strength, the construction of a section insulator becomes decidedly bulky when hickory is used.

Resinous compounds have been used as insulating material in section insulators, but while they have good electrical qualities, they do not have the mechanical strength to withstand the high stresses imposed upon them. In some cases, rubber compounds have been used but while they have both the desirable mechanical and electrical properties, their cost is excessive, as also is their weight.

It may, therefore, be seen that with the continued rapid growth of trolley-bus systems, and with the increasing scarcity of hickory as an insulating material, there is a decided need for some new material or combination of materials to give an insulator the desired electrical and mechanical qualities.

The object, therefore, of my invention is to provide a high strength, single beam section insulator which will have high resistance to the deleterious effects of exposure to moisture.

Another object of my invention is to provide a super-rigid single beam section insulator that shall not swell, buckle or warp under the most adverse weather conditions.

A further object of my invention is to provide a super-rigid section insulator having renewable wearing parts.

Another object of my invention is to provide a section insulator having an insulating member with a metallic core of magnetic material, which functions to greatly reduce or prevent the burning of the insulating member by the arc.

Still another object of my invention is to provide a weather proof super-rigid beam section insulator that shall be protected from the destructive effects of arcing.

A still further object of my invention is to provide a single beam section insulator having a core of interlocking metal strain plates molded in an insulating material and renewable insulating wearing parts designed to protect the main body from destructive effects of arcing.

Other objects will in part be obvious and in part appear hereinafter.

My invention, accordingly, is disclosed in embodiments hereof shown in the accompanying drawing, and comprises the features of construction, combination of elements, arrangement of parts which will be exemplified in the construction hereinafter set forth, and in the scope of the application of which will be indicated in the appended claims.

For a more complete understanding of my invention reference may be had to the following detailed description, taken in connection with the accompanying drawing, in which:

5 Figure 1 is a partially-sectionalized plan view of a trolley section insulator embodying the principal features of my invention, showing one preferred method of construction.

10 Fig. 2 is a side elevational view of the section insulator of Fig. 1.

Fig. 3 is a sectional view taken along the line III—III of Fig. 2, and

Fig. 4 is an end elevational view of Fig. 2.

15 Referring more particularly to Figs. 1 and 2, the reference character 10 denotes a beam section trolley insulator embodying my invention. The insulator 10 comprises generally a longitudinal beam insulating member 11 having end fittings 12, such as shown, of well-known construction, 20 secured thereto for engaging adjacent ends of a trolley wire 13 or other well known forms of fixtures.

25 In one form of my invention, in order to secure the necessary tensile strength and insulating qualities, the beam 11 may comprise both insulating material and metallic members formed as a unitary member. In this instance, the beam 11 comprises similar metallic strain members 15 which function as a metallic core for the beam 30 and through which the bolts 16 extend to secure the end fittings 12 in position.

35 As will be readily understood, the metallic members 15 must not only be securely joined together but must be insulated from one another. They may be jointed together by means of a joint comprising two complementary beveled surfaces having a plurality of interlocking members thereon, such as the flaring tenons 17. These surfaces are so disposed that the tenons 17 40 of the one strain member 15 are positioned in the grooves 18 of the other strain member. Suitable insulating material 19 is interposed between the interlocking tenons 17 and grooves 18 to maintain the strain members 15 in fixed relation and 45 insulate them from each other.

50 To aid in binding the strain members 15 together and to protect the insulating material 19 from exposure to the weather, an enveloping insulating shell 21 may be provided about the interlocked strain members 15 in any suitable manner, such as by winding impregnated paper or cloth about them under pressure from heated rolls. This provides a unitary beam structure 55 having the necessary strength and insulating qualities.

55 In order to relieve the body member 11 from wear and the destructive effects of arcing, an insulating sheath 22 may be detachably secured to the lower side of the body member 11 in any well known manner, such as by insulating bolts 23 passing through the body member 11.

60 The insulating sheath 22 may be formed in any desirable manner, such as a U-section channel having flaring sides which tend to disperse an arc away from the body member as it rises, thus protecting the body member 11 from the burning effects of arcing.

65 It has been observed that a section insulator of a type embodying my invention has shown additional advantages. Where the metallic strain members of the insulating member have comprised a magnetic material, such as iron, improved electrical performance as well as mechanical strength has resulted.

70 It appears that under normal operating conditions section insulators are exposed to serious arcing as the current collector leaves the line section of the conductor. This arcing is usually most destructive not only to the end fittings of 5 the insulator but to the insulating member also.

With a section insulator embodying my invention, however, it has been observed that such an arc may be drawn and the end fittings may even be severely burned, without any appreciable damage resulting to the insulating member where the strain members are of a magnetic material. It is therefore obvious that the inclusion in the vicinity of the arc of the magnetic material of the reinforcing members has certain desirable 15 effects, tending to draw the arc out, cool it, and reduce its harmful burning effects.

10 It may be seen, therefore, that my invention provides a single beam section insulator which not only combines high tensile strength, high 20 insulating value and immunity to moisture, but which uses well known fittings, is easy to manufacture, and inexpensive to maintain.

15 Since certain further changes may be made in the foregoing construction, and different embodiments of the invention may be made without departing from the scope thereof, it is intended that all the matter set forth in the foregoing description or shown in the accompanying drawing 25 shall be considered as illustrative and not in 30 a limiting sense.

I claim as my invention:

1. A single-beam section insulator for overhead trolley systems, comprising, in combination, a main insulating member formed with a pair 35 of similarly shaped relatively thin interlocked metallic reinforcing members therein, the insulating material of said insulating member being formed about and between said reinforcing members to secure them in fixed relation with each 40 other, end means secured to the main member disposed to secure adjacent ends of a trolley wire, and a renewable wearing surface and arcing shield having outwardly flaring sides detachably secured about the under side of the insulating member. 45

2. A beam insulator for overhead trolley systems comprising, in combination, an insulating main body member having a pair of similar reinforcing metallic members oppositely disposed in spaced relation and separated and enveloped 50 by an insulating sheath to provide a unitary body member, end fittings for securing the main body member in operating relation in the overhead system, and a removable arcing shield and wearing surface secured about the runner edge 55 of the main body member.

3. A beam insulator for overhead trolley systems comprising, in combination, an insulating body member having a pair of similar overlapping reinforcing members of magnetic material disposed within said body member in parallel spaced relation, a laminated sheath of fibrous insulating material formed about and between said members to provide a unitary structure, end members secured to the body member adapted to position 60 said body member, and a fixed wearing sheath removably secured about the under side of the body member to provide a renewable wearing surface and an arc shield for said body member. 65

4. In a single beam insulator for trolley systems, in combination, a main insulating body member including a pair of thin tapered interlocking metal plates overlapping in opposed relation, insulating material between the plates disposed to hold them apart to maintain them in 70 75

fixed relation to each other, a plurality of layers of impregnated fibrous insulating material moulded about said plates, and detachable end means secured to the body member disposed to position 5 said body member in the trolley system.

5. In an insulator of the single beam type, in combination, a body member comprising a pair of interlocking end plates, insulating material disposed between the end plates to hold them 10 apart, and a shell of insulating material disposed about the plates, terminal members secured to each end plate disposed to engage adjacent ends of a trolley wire, and a renewable sheath of insulation disposed to provide a wearing surface and arc-shield secured to one edge of the body member.

15 6. An insulator of the single beam type for trolley systems comprising, in combination, a main insulating body member including a pair 20 of tapered interlocking metal reenforcing end plates formed within the body member and separated by the insulating material of the member, end means secured to the body member for positioning said body member in a trolley system, and 25 a renewable under-run and arc-shield having outwardly inclined upstanding edges adapted to enclose an edge of the main body secured about the lower edge thereof.

7. An insulator of the single beam type for 30 trolley systems comprising, in combination, an insulating main body member having a pair of similar tapered metallic reenforcing members dis-

posed therein in insulated interlocking relation to relieve the insulating material of incident strain, end means secured to the ends of the body member adapted to position the insulator in the trolley system, and a renewable wear portion and arc 5 shield having outwardly flaring upstanding sides secured about an edge of the body member.

8. A section insulator for trolley systems, comprising, in combination, a main insulating member having a reenforcing core of overlapping 10 metal strain plates so disposed within the main member and insulated from each other that the insulation of the insulating member surrounds said strain plates and maintains them in fixed relation with each other, means secured to the 15 ends of the main member disposed to position the body member in a trolley system, and a detachable wearing sheath and arc-shield secured to the under side of the main member.

9. A section insulator for trolley systems comprising, in combination, a longitudinal insulating beam member of at least two overlapping and interlocking metal plates separated by and enveloped by an insulating material disposed to insulate the plates from each other and to maintain them in fixed relation, end means secured to the beam member for engaging adjacent ends 20 of a trolley wire, and a sheath of insulating material detachably secured to the lower edge of the beam to provide a renewable wearing surface and 25 arc-shield.

LON C. SPENCER.
